SCREEN

Orrie J. Mills, Hudson Falls, and William G. Webb, Glens Falls, N. Y.

Application June 6, 1932. Serial No. 615,670

10 Claims. (Cl. 92—32)

The present invention relates to improvements in screens and more especially to flat screens of the type adapted for use in screening paper pulp and similar materials in making paper and similar products and employing diaphragms beneath the screen surface for forcing liquid having the pulp stock suspended therein back and forth through the screen surface and thereby effecting or facilitating the screening action.

One of the primary objects of the invention is to provide a novel and improved screen of this class wherein each diaphragm beneath the screen surface slopes laterally toward a flow box extending longitudinally of the screen and the space or chamber between the diaphragm and the screen surface communicates directly with the flow box whereby the stock is caused to flow more rapidly from such chamber into the flow box and the collecting of dirt or slime on the surface of the diaphragm chamber is minimized or prevented.

Another object is to provide such a screen wherein the outlet from the chamber beneath the screen surface and above the diaphragm to the flow box is relatively large and direct and is provided with a gate for varying its effective size, thereby enabling the degree of vacuum and pressure exerted in drawing the pulp downwardly and forcing mostly air and some liquid upwardly through the screen surface to dislodge unscreened stock to be regulated according to the sizes of the slots or perforations in the screen surface used and to best suit different kinds of stock to be screened, thereby increasing the efficiency of the screening action and, in consequence, the capacity of the screen, and reducing the amount of power required to operate the screen, and also enabling the dam for the discharge of the pulp from the flow box to be set at a lower level than usual, thereby further increasing the capacity of the screen.

Another object is to provide means whereby any number of screen plates composing the screen surface may be cleaned by introducing water or other cleaning fluid into the chamber or chambers beneath them, without interrupting the performance of the screening operation by the remainder of the screen plates and without the necessity of lifting the screen plates, as heretofore required, thus enabling the cleaning operation to be performed with greater speed and facility and while the screen continues in operation.

Further objects of the invention are to provide novel and improved operating means for the diaphragms whereby the weight of the latter and the operating means are substantially balanced,

thus enabling the diaphragms to be driven by less power than usual to provide simple and effective means for lubricating the elements of the operating means, and to improve and simplify the construction of the diaphragm operating means in other respects.

To these and other ends, the invention consists in certain improvements and combinations and arrangements of parts all as will be herein-after more fully described, the features of novelty being pointed out particularly in the claims at the end of the specification.

In the accompanying drawings:

Fig. 1 is a side elevation, partly in section, of a flat pulp screen of the diaphragm type constructed in accordance with the present invention;

Fig. 2 is a top plan view, partly in section, of the screen shown in Fig. 1;

Fig. 3 is a transverse vertical section, on an enlarged scale, taken on the line 3—3 in Fig. 1; and

Fig. 4 is a detail view, partly in section, showing a modification of the diaphragm operating means.

Similar parts are designated by the same reference characters in the different figures.

The invention is shown in the present instance as applied to a flat pulp screen of the diaphragm type, it embodying a base 1 which may be of metal or any other suitable construction, a frame 2 supported on the base, this frame being of a length and width conforming with the dimensions of the screen, and a screen vat 3 which is mounted on and supported by the frame 2, this vat containing the screen surface which is preferably composed of slotted or otherwise perforated screen plates 4 the number of which may vary according to the desired capacity of the screen, eight of these screen plates being shown for example in the present instance. These screen plates may be supported in stationary position in the bottom of the screen vat in any suitable manner, they being shown in the present instance supported by the longitudinal strips 5 secured to the inner sides of the longitudinal side walls of the vat and by transverse members 6 and 7. The screen plates are preferably grouped in pairs, the adjacent edges of the plates of each pair being supported by the transverse members 7 and the outer edges of these plates being supported by the transverse members 6, the latter resting on and forming fluid-tight joints with cross members 8 of the frame 2, so that separate or non-communicating chambers 9 are formed beneath the pairs of screen plates.

The bottom of each chamber 9 is closed by a

110

flexible vibratory diaphragm 10 which may be composed of a sheet of rubber or of rubber and fabric, and according to the present invention, this diaphragm is inclined downwardly and laterally toward one side of the screen, its peripheral edge being secured to and forming a fluid-tight joint with a ledge 11 formed on the frame 2 and the transverse members 8. The diaphragm is provided with means for vibrating it in a direction transverse to its plane, such means, according to the present invention, comprising a rocker lever 12 which is pivoted intermediately of its ends on a pivot pin 13, one end of this lever being bolted or otherwise secured to the lower end of a spring steel plate 14 and the upper end of the latter being bolted or otherwise fixed to a plate 15 beneath the diaphragm, the diaphragm being clamped between this plate and an upper plate 16. The spring steel plate 14 is bolted to the diaphragm plate 15 so that it extends perpendicularly to the plane of the diaphragm, in consequence of which rocking movements of the lever 12 and which cause reciprocations of the plate 14 will vibrate the diaphragm to equal extents at all points around its circumference.

The wall of each chamber 9 which is at the lowest edge of the diaphragm 10 is provided with an outlet passage 17 which leads from said chamber above the diaphragm, and this passage leads into a flow box 18 which extends longitudinally along that side of the screen and communicates with the similar outlet passages from the other chambers and serves to collect the screened pulp therefrom. Each outlet passage 17 is provided with a gate 19 which is preferably arranged at the outer end of said passage and is guided to move vertically, this gate serving to cover more or less or to fully uncover the passage 17 and thereby vary its effective area, or the gate 19 may be fully lowered to completely close said passage. Any suitable means may be employed for adjusting the gates 19, they being preferably independently or individually adjustable, each gate being provided for this purpose in the present instance with a screw 20 which extends upwardly therefrom and a nut or head 21 which is threaded on the screw and supported by the adjacent wall of the flow box so that rotation of the nut or head in the appropriate direction will raise or lower the respective gate and thereby vary the effective area of the corresponding outlet passage 17 or will completely open or completely close this passage, as occasion may require. The flow box is divided longitudinally by a partition 22 above which extends a dam 23 which is adjustable vertically in the flow box to vary the height of its upper edge, the ends of the dam being shown in the present instance as guided to move vertically in grooves 24 formed in the end walls of the flow box and provided with screws 25 and cooperating nuts or heads 26 which are adjustable to raise and lower the dam as occasion may require. The dam divides the portion of the flow box into which the outlet passages 17 discharge from the compartment 27 thereof from which the screened stock discharges, the stock overflowing the upper edge of the dam to reach the discharge compartment 27. The screened stock may discharge from the compartment 27 of the flow box through an outlet pipe 28 leading from the bottom thereof. The stock to be screened is fed to one end of the screen vat by a chute or other suitable means 29, the pulp stock suspended in water or other liquid flowing longitudinally of the screen, over the screen plates and toward the opposite end of the screen.

The diaphragms are vibrated, during the operation of the screen, by the rocker levers 12 connected thereto in the manner above described, these rocker levers being actuated by a cam shaft 30. According to the present invention, the rocker levers 12 extend outwardly from beneath the respective diaphragms to points beyond a longitudinal side of the screen, and the cam shaft 30 is also mounted beyond a side of the screen so that the operating mechanism for the diaphragms will be readily accessible for inspection or repair and will be out of the path of any leakage of pulp from the screen which would impair the operative condition thereof. Preferably and as shown, the rocker levers and cam shaft are supported by a longitudinal girder 31 which is preferably composed of a one-piece casting or fabricated steel of rigid construction, it extending longitudinally at one side of the screen and being bolted or otherwise secured at its ends to the end members of the base 1. The inner side of the girder 31 is provided with an inward extension 32 for each rocker lever 12, each of these extensions supporting a stationary pivot pin 13 on which the respective lever 12 is journaled. The cam shaft 30 is mounted in a suitable number of bearings 34 supported along the top of the girder, and the cam shaft has cams 35 fixed thereon, one cam being provided for each diaphragm operating lever 12. The outer end of each lever 12 may be provided with an open top bearing 36 for a journal 37 of a pair of rollers 38, these rollers bearing against the underside of the respective cam 35. As an alternative, the outer end of each diaphragm actuating lever 12 may be formed with a socket 39 and clamping screw 40 to receive and hold a toe block 41 composed of hard wood, fiber or other suitable wear-resisting material, this toe block bearing against the underside of the respective cam. In either case, the bottom of the girder 31 has an opening 42 extending upwardly therethrough, this opening being surrounded by an upturned flange 43, and a coiled compression spring 44 extends upwardly through this opening and bears against the underside of the lever 12, this spring forcing the rollers 38 or the toe block 41 toward the respective cam 35 with sufficient pressure to maintain the rollers or the toe block in contact with the cam, thereby insuring full downward or suction strokes of the diaphragm. The power of each of these springs may be adjusted by a suitably arranged screw 45, this screw being shown for example supported on the underside of the girder and bearing against the lower end of the respective spring.

The lower part of the girder forms an oil well 46 which extends throughout its length, and the rollers 38 are partly immersed in the oil in this well and thus pick up oil therefrom to lubricate them and the cams. In order to insure lubrication of the bearings of the levers 12 which engage the pivot pins 13, the top of each lever is provided with a well 47 which is adjacent to the rollers 38 so that it will receive oil picked up by these rollers, and an oil duct 48 leads from the well 47 at an incline to an oil hole 49 in the hub of the lever 12 and which leads to the bearing of the lever which engages the pivot pin 13. The upturned flange 43 surrounding each opening 42 in the bottom of the girder prevents leakage of the oil therethrough and the girder, which is trough-shaped, provides an oil well throughout its length, for supplying oil to the operating means for all of the diaphragms.

of the series. The cam shaft 30 is driven continuously at an appropriate speed by a belt pulley 130 fixed thereto or by any other suitable means.

To enable the screen plates to be easily and quickly cleaned when necessary, a pipe 50 is provided along one side of the screen vat, this pipe having branches 51 which lead into the respective chambers 9 through the sides thereof at the highest edges of the sloping diaphragms there-in and are provided with individual controlling valves 52. The pipe 50 is adapted to supply water or any other suitable cleaning fluid, the individual valves provided enabling the water or cleaning fluid to be introduced into any one or more of the chambers, without disturbing the screening operation in the remaining chamber or chambers.

The operation of the screen is as follows:

The pulp, suspended in water or liquid as usual, so that it is fluid, is supplied to one end of the screen by the chute 29, it flowing onto the screen plates and travelling longitudinally toward the opposite end of the screen, and during the operation of the screen, the cam shaft 30 is driven at a suitable speed, the cams 35 thereon rocking the series of rocker levers 12 and causing them to vibrate the respective diaphragms 10 in a direction perpendicular to the plane thereof. The gates 19 are suitably adjusted according to the size of the slots or perforations in the screen plates used and to the fineness or other characteristics of the pulp undergoing screening, and the dam 23 in the flow box is adjusted to maintain the liquid level at the proper height in the chambers 9 with respect to the screen plates, this liquid level being normally immediately below the screen plates. The vibratory movements of the diaphragms produce alternately a suction or partial vacuum in each chamber 9 which acts to forcibly draw the pulp downwardly through the screen plates and to produce a pressure in the chamber 9 which acts to force mostly air and some liquid below the screen plates upwardly through the perforations therein, such alternate suction and pressure agitating the pulp on the screen plates and thus promoting and facilitating the screening action. The screened pulp which passes through the screen plates into the chambers 9 flows outwardly therefrom through the respective outlet passages 17 into the flow box 18 and then overflows the upper edge of the dam 23 into the discharge compartment 27 whence it may be conducted to any desired point for further treatment in the making of paper or for other purposes, according to the nature of the pulp treated.

By inclining or sloping each diaphragm 10 laterally and downwardly toward the flow box at the side of the screen the accumulation of dirt or slime on the upper surface of the diaphragm, as takes place rapidly on the usual diaphragm screens, is substantially avoided since the slope of the diaphragm toward the respective outlet passage 17 and flow box insures the gravity flow of the pulp stock and all other matter in suspension in the water or liquid directly through the outlet passage and into the flow box. Such lateral slope or inclination of each diaphragm also enables a straight and direct outlet passage to be formed between each chamber above the diaphragm and the flow box, thereby permitting a more rapid and unimpeded flow of the pulp from beneath each screen and into the flow box. Furthermore, the lateral slope or

inclination of each diaphragm enables an outlet passage to be used which is much larger than has heretofore been possible, it enabling an outlet passage to be used for each vacuum and pressure chamber which has an area equal to or greater than the aggregate area of the slots or perforations in the respective pair of screen plates, so that the flow of the pulp through the screen plates will not be obstructed or impeded by the outlet passage.

The lateral slope or inclination of the diaphragm in conjunction with the outlet passage 17 of large area and controlled as to its effective area by the gate 19 enables increased efficiency in the screening operation and increased capacity of the screen to be obtained since the effective area of the discharge passage 17 may be adjusted by the gate 19 to regulate the degree of vacuum and pressure produced in the chamber 9 by the diaphragm according to the size of the perforations in the screen plates and the character of the stock being screened and to permit the outflow of the stock from the chamber 9 as rapidly as the screening operation takes place, it being understood that when screen plates having relatively small perforations therein are used or relatively long fibered stock is being screened, the gate 19 will be lowered to reduce the effective area of the outlet passage 17 and thereby increase the degree of vacuum and pressure produced in the chamber 9, and when screen plates having relatively large perforations therein are used or relatively short fibered stock is being screened, the gate 19 will be adjusted to a relatively higher position to provide a relatively larger effective area for the outlet passage 17, thus enabling the degree of vacuum and pressure to be varied in any case to produce efficient and rapid screening action and prevent clogging of the screen plates, the variations of the effective area of the outlet passage 17 by the lowering or lifting of the respective gate 19, damping or retarding more or less the pulsations of the pulp through said passage incident to the vibrations of the diaphragm and consequently increasing or reducing the intensity at which the pulp is forced vertically through the screen plates, this result being accomplished without the necessity of varying the throw of the cam or other parts of the diaphragm operating means.

The provision of the gates 19 in conjunction with the vertically adjustable dam 23 in the flow box enables greater efficiency in the screening operation and increased capacity of the screen to be obtained, since the gates 19 enable the most effective vacuum and pressure actions to be obtained on the screen plates and the dam 23 enables the pulp to be maintained at the most effective level beneath the screen plates while permitting the screened pulp to flow out of the chambers beneath the screen plates as rapidly as the screening action permits. Since the gates 19 are adjustable independently of the dam 23, and, as shown, are located below the level of the top of said dam and hence are submerged in the pulp, they may be set or adjusted to obtain any desired intensity of vacuum and pressure beneath the screen plates, without being limited by the height of the liquid or pulp in the flow box as determined by the dam 23.

The lateral sloping of the diaphragms and the provision of the gates for regulating the degree of suction and pressure exerted on the screen plates minimizes the necessity of cleaning the

diaphragms of accumulated dirt or slime or the screen plates due to clogging. The present invention, however, provides means for effectively cleaning the diaphragms and screen plates without the necessity of removing the screen vat from the frame as heretofore required. Any one or more of the diaphragms and the respective screen plates may be cleaned, according to the present invention, by fully lowering the respective gate 10 or gates 19 and thereby completely closing the respective discharge passages 17, and opening the valve or valves 52 so that water or other cleaning fluid is introduced from the supply pipe 50 into the respective chamber or chambers 9, and this may be done while the screen is in operation, since each of the chambers 9 is entirely separate or non-communicating with respect to the others so that the screening operation may continue without interruption in the other chambers. The water or cleaning fluid thus introduced into the chambers 9, the diaphragms and screen plates of which are to be cleaned, serves to dislodge any dirt or slime accumulated on the upper sides of the respective diaphragms and to be carried upwardly through the screen plates by the flow of the water or washing fluid, this upflow of the water or washing fluid through the screen plates serving to unclog them, and this unclogging action is assisted by the alternate 25 vacuum and pressure or agitating action of the vibratory diaphragm. The matter thus dislodged by the washing fluid is carried on to other screen plates in the series which are performing their screening operation and is thereby rescreened. By thus enabling one or more of the 30 units of the screen to be washed while the remaining units thereof continue their screening operation, interruption of the operation of the entire screen is avoided, thereby saving much 35 time and increasing the output of the screen.

The increased efficiency in the screening action obtained by regulating the degree of vacuum and pressure according to the size of the screen plates used and the character of the stock being 40 screened and the regulation of the liquid or pulp level below the screen plates according to the rapidity of the screening operation increases the capacity of the screen or enables a screen to be used having a smaller number of screen plates to obtain a given capacity and also enables the cam shaft to be driven at a speed lower than that usually required in screens of this type, thus saving power in the operation of the screen.

By mounting the cam shaft above the roller or toe block end of the rocker lever, the opposite end of which is connected to the diaphragm for vibrating it and substantially balancing the weight of the diaphragm and the pulp above it by the cam shaft, a saving in the power required 50 to vibrate the diaphragms is obtained, particularly since the cam shaft will be supported so that it substantially floats in its bearings.

We claim as our invention:

1. A screen comprising a vat containing a 60 screen plate, a flow box extending longitudinally at one side of the vat, and a vibratory diaphragm closing the bottom of a chamber between it and the screen plate and sloping downwardly toward the flow box, such chamber having an outlet passage extending laterally through the side thereof which is at the lowest edge of the diaphragm and forming direct communication between said chamber and flow box.

2. A pulp screen comprising a vat containing 70 a screen plate, a flow box at a side thereof, a

chamber beneath the screen plate having an outlet passage in the side thereof adjacent to the flow box and communicating therewith, and a vibratory diaphragm closing the bottom of said chamber and sloping laterally and downwardly 80 toward the flow box and to a level below said outlet passage for the direct discharge of screened pulp from said chamber through said outlet into the flow box.

3. A pulp screen comprising a vat for the longitudinal flow of the pulp therein and containing a flat screen surface, a flow box at a side of the vat, a chamber beneath the screen surface, and a vibratory diaphragm forming the bottom of said chamber and sloping downwardly toward the flow box, the side wall of said chamber at the lowest edge of the diaphragm being adjacent to the flow box and said wall having an outlet passage extending laterally therethrough at a level above said lowest edge of the diaphragm 90 and leading from said chamber to the flow box for the direct discharge of pulp from said chamber above the diaphragm to the flow box.

4. A pulp screen comprising a vat containing a screen surface, a chamber beneath said surface, a vibratory diaphragm operative to produce alternate pressure and vacuum conditions in said chamber, an outlet passage leading from said chamber, a dam to receive pulp from said outlet passage and control the level of pulp in said 100 chamber, and a gate the lower edge of which is below the level of the top of the dam and is adjustable to different distances above the bottom of said outlet passage to vary the effective area thereof.

5. A pulp screen comprising a vat containing a screen surface, a chamber beneath said surface, a vibratory diaphragm operative to produce alternate pressure and vacuum conditions in said chamber, a flow box, an outlet passage leading 110 from said chamber to the flow box, the flow box having a dam the height of which is adjustable to control the level of the pulp with respect to the screen surface, and a gate located below the level of the top of the dam and adjustable relatively to the dam to vary the effective area of said outlet passage and thereby govern the degree of pressure and vacuum produced in said chamber by the diaphragm.

6. A screen comprising a vat containing a 125 screen surface, a vibratory diaphragm spaced beneath said surface, said diaphragm sloping downwardly toward one of its edges, a chamber enclosing the space between the screen surface and diaphragm, an outlet passage leading from the 130 side of said chamber at the lowest edge of said diaphragm, means for closing said outlet passage, and means for introducing a washing fluid into the side of said chamber at the highest edge of said diaphragm.

7. In a screen comprising a vat containing a screen surface and a vibratory diaphragm beneath said surface, a rocker lever having a member connected to one end thereof and attached to the diaphragm, and a cam shaft mounted 140 above the other end of said rocker lever for actuating it and the diaphragm and for substantially balancing the weight of the diaphragm.

8. In a screen comprising a vat containing a screen surface and a vibratory diaphragm beneath it, a pivoted rocker lever connected at one end to the diaphragm for vibrating it, a cam shaft mounted above and operative upon the other end of said lever for rocking it, an oil reservoir containing the pivoted and cam shaft 145 150

operated portions of said lever for supplying oil thereto, the bottom of said reservoir having an opening therein and an upturned flange surrounding such opening, and a spring extending through said opening in the bottom of the reservoir and bearing on the underside of said rocker lever to retain it in operative relation with the cam shaft.

9. In a screen comprising a vat containing a screen surface and a flexible vibratory diaphragm beneath it, a pivoted rocker lever, a flexible member rigidly fixed at its ends respectively to one end of said lever and to the diaphragm and extending perpendicularly to the plane of the diaphragm, and means for rocking said lever to vibrate the diaphragm.

10. In a screen comprising a vat containing a screen surface and a vibratory diaphragm beneath it, a pivoted rocker lever connected at one end to the diaphragm, a roller on the other end of said lever, a cam engaging the upper side of said roller to rock said lever and vibrate the diaphragm, and a reservoir to contain oil in which said roller is immersed, the upper side of the rocker lever having a well to receive oil lifted by said roller from the reservoir and having a duct leading to the pivot of the lever for conducting oil thereto from said well.
